Mar. 15, 2023—(CN) Office Action—App. No. 201880035443.0.
(Continued)*Primary Examiner* — Christy Nemeth*(74) Attorney, Agent, or Firm* — Banner & Witcoff, Ltd.**CLAIM**

The ornamental design for an insulating device as shown and described.

DESCRIPTION

FIG. 1 is a top, front, left perspective view of an insulating device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the insulating device that form no part of the claimed design.

1 Claim, 5 Drawing Sheets
